UNITED STATES PATENT OFFICE.

WALTER EDWARD KIMBER, OF JOHANNESBURG, TRANSVAAL.

APPARATUS FOR SHARPENING DRILLS OR DRILL-BITS.

No. 902,416.

Specification of Letters Patent.

Patented Oct. 27, 1908.

Application filed July 10, 1906. Serial No. 325,489.

To all whom it may concern:

Be it known that I, WALTER EDWARD KIMBER, a subject of the King of Great Britain, and resident of Johannesburg, 5 Transvaal, have invented certain new and useful Improvements in Apparatus for Sharpening Drills or Drill-Bits, of which the following is a specification.

This invention relates to machines or apparatus for sharpening drills or drill bits employed for drilling holes in rock in mining and other similar work.

It is designed to construct a machine in or by means of which the drills or bits may be sharpened in a more efficient and expeditious manner than at present, thereby enabling the sharpening to be effected with less labor and consequently at less expense.

In the accompanying drawings forming 20 part of this specification I illustrate a practical embodiment of the invention adapted for the sharpening of the cruciform drill or bit commonly known as a "star bit".

In the drawings, Figure 1 represents the 25 machine in longitudinal part sectional elevation, Fig. 2 is an end elevation of the same, Fig. 3 is a front elevation, partly in section, of the two sets of tools which operate longitudinally on the wings of the drill or bit to 30 forge and size the same, and the means for actuating said tools. Fig. 4 is a detail view of a portion of the periphery of the disk 4, illustrating the guideway 8 for one of the tools, the recess in said guideway for the 35 spring, and the spring which operates to maintain the tool in its expanded or outer position. Fig. 5 is a transverse section of the table (the plane of section being indicated on the line $x-x$ of Fig. 1) illustrating the 40 movable and adjustable stop for the shank end of the drill or bit. Fig. 6 is a plan of the self-centering vise, and Fig. 7 is a front elevation of the dolly.

In Figs. 1 and 2, 1 designates a foundation 45 or bed plate, which serves for carrying the several parts of the machine at a convenient height. The bedplate 1, in proximity to one end thereof, is constructed with or has bolted or otherwise conveniently fixed to it, a vertical frame or support 2. This frame 2 is constructed with a cylindrical or other suitably shaped hole 3 in its upper portion. The frame 2 serves for carrying the forging tools or the tools for shaping the drill or bit 50 or operating between the wings for imparting to it the cruciform section, and the tools

for sizing the drill or bit, for rounding the wings and tapering the wings longitudinally or for putting the proper clearance on the sides of the wings. For performing these 60 operations two sets of tools are employed and they are operatively carried by means of a stationary disk 4. The disk 4 is constructed with a hollow cylindrical projection 5 at the back, and the outer end of the cylindrical projection 5 is formed with an inwardly directed flange 6 which serves for bolting said disk to its vertical support 2. The flange 6 forms a central aperture coinciding 65 with the aperture 3 in the vertical support 2. 70 The disk 4 is constructed with a central hole 7 and with eight radial slots 8, which form guideways for the two sets of forging tools. The several tools are retained in position in their guideways 8 by means of a ring 75 8^a fixed by means of bolts 8^b to the disk 4.

The tools marked 9 are the shaping tools or those which operate between the radial wings 10 of the cruciform drill steel to impart to it the requisite symmetrical cruciform section. The other set of four tools 11 are the tools which operate to put the requisite clearance or taper longitudinally of and in the direction of the shank 12 on the sides or outer edges of the wings 10 of the drill, 80 and for rounding the wings and also for sizing the drill.

While I prefer to use steel of cruciform section it will be apparent that the machine may be used for forging the cruciform or 90 star section out of the ordinary octagonal or other suitable section of drill steel.

The inner extremities of the four tools 9 are of L shape to operate between the wings while the other four tools 11 are rounded 95 and inclined longitudinally to form the taper and impart the rotundity to the sides of the wings 10. Each of the tools 9, 11, has fixed to it a pin 13 which traverses a radial slot 14 formed through the front ring 8^a. 100 This pin 13 and slot 14 serve for limiting the outward movement of the several tools 9, 11. The several tools 9, 11, are also constructed at their outer ends with a projection 15 and in the guideways 8 at one side, is 105 formed a recess 16. In this recess 16 and resting at one end in the bottom of the recess and at the other end engaging the projection 15, is a spiral spring 17 which serves for maintaining the tool in its expanded or 110 outermost position or with the pin 13 engaging the outer end of the slot 14.

The outer ends of the several tools 9, 11, project slightly beyond the circumference of the disk 4, as shown more particularly in Fig. 3, and they are curved or inclined as indicated at *a* from the one edge to the other.

Round the disk 4 is arranged an oscillating ring consisting of two annular or approximately annular pieces 18 connected by the four circumferential or peripheral webs 19. The oscillating ring is constructed with a cylindrical projection 20, the internal diameter of which approximately corresponds to the external diameter of the cylindrical projection 5 on the disk 4, which cylindrical projection 5 constitutes a bearing for said oscillating ring 18. In the oscillating ring 18 are arranged four rollers 21 which are revolvably mounted on four pins 22 fixed between the two annular parts 18 of said ring. The diameter of these rollers 21 is such that they are adapted, when the ring is oscillated, to simultaneously engage the curved outer extremities of either set of tools 9, 11, and to alternately move each set inwards in their guideways 8 so that their inner ends operate to forge the bit when it is placed in position. When the ring 18 is moved in one direction it simultaneously actuates the four tools 9, and when moved in the reverse direction it in like manner simultaneously operates the other four tools 11. When the tools 9, 11 are alternately operated as described, the springs 17 are placed in compression so that they operate when the rollers 21 disengage the outer ends of the tools 9, 11, to expand them or force them in an outward direction. The portions 4^a of the circumference of the disk 4, permit the rollers 21 to revolve freely after disengaging the one set of tools and before engaging the other set. By the means described it will be evident that by oscillating the ring 18 or moving it through portion of a revolution first in one direction and then in the other direction and then bringing it into a central position or midway between the tools 9, 11, or with the rollers 21 engaging the portions 4^a of the circumference of the disk, (in which position it is shown in Fig. 3,) first one set of tools is actuated to operate on the drill or bit, then the other set, and then when the rollers take up the position shown in Fig. 3, all the tools are permitted to expand or stand apart clear of the drill or bit *b*. This mode of actuating the forging and swaging tools 9, 11, constitutes an extremely important feature of the present invention, as by having all the swaging and forging tools clear of the drill or bit when the dolly is brought into operation, permits of the proper operation of said dolly.

On the back of the oscillating ring 18 is formed a projection 22^a and on the vertical part of the frame 2 are formed two projections 23 through which are formed holes in

which are positioned adjustable stops 24. In the other ends of the holes are screwed adjusting screws 25 and between the inner ends of the adjusting screws 25 and the inner ends of the stops 24 are placed spring-buffers 26. The outer extremities of the adjustable resilient stops 24 are adapted to be engaged by the projection 22^a on the oscillating ring 18 and by their position to determine the extent of the oscillatory movement transmitted to said ring 18, and by that means determine the movement transmitted to the forging and swaging tools 9, 11. When the movement of said oscillating ring is limited, it reduces the movement of the tools 9, 11. This permits of any desired adjustment of the tools 9, 11 being effected to operate on varying sizes of drills or bits, and obviates all necessity for substituting or changing the tools to sharpen drills of varying size.

For the purpose of oscillating the ring to actuate the forging and swaging tools 9, 11, an oscillating cylinder 27 is mounted on the bedplate 1 of the machine—see Fig. 2. The piston rod 28 working in this cylinder 27 is attached, as indicated at 29, to the oscillating ring 18. Means, such as are employed in a steam hammer are provided for controlling the admission of the actuating fluid to the oscillating cylinder 27 to vary the force with which the forging tools and swages operate on the drill or bit. A bracket 30 is shown fixed to the frame 2, to which bracket 30 is pivoted a bell-crank lever 31, to one arm of which is fixed a handle 32 and to the other arm the valve rod 33. By means of said handle 32, bellcrank 31 and valve rod 33, the movement of the valve is controlled by the operator to admit the actuating fluid to the cylinder 27 to actuate the oscillating ring 18.

At the rear of the vertical frame 2 and formed upon or fixed to the bedplate 1, is a standard 34 which serves for carrying the hammer which actuates the dolly. 35 is the cylinder of the hammer and 36 the striker. The forward portion 37 of the hammer cylinder serves as a guide for the dolly. 38 is the dolly (shown in front elevation in Fig. 7) constructed with a shank 39 which projects into the bore of the forward end of the hammer cylinder 35. The inner end of the shank 39 is reduced and on its inner end it receives the impacts of the striker 36. The forward end of the hammer cylinder 35 is shown constructed with a recess 40. In this recess 40 and bearing against the back of the dolly 38 is a spring 41 which keeps the dolly 38 in position on the end of the drill while it is being struck. The dolly 38, which serves to upset the drill or bit, is formed with V grooves 42, see Fig. 7, which intersect at the center and operate to form the cutting edges along the radial ends of the wings 10 of the drill. To the dolly 38 is attached a

hook 43 which is connected to a rod 44. The rod 44 is pivotally attached at its other extremity to a lever 45, which latter is pivoted to a lug 46 formed on the standard 34. 5 This lever 45 works in a quadrant 47 and is fitted with a trigger 48 which is adapted to engage a notch or recess 49 in the quadrant 47. The lever 45 is provided for retracting the dolly 38 while the drill is being operated 10 upon by the forging tools and swages, the trigger 48 serving to maintain the lever 45 and dolly 38 in this position. When the lever 45 is released by disengaging the trigger 48, the spring 41 moves the dolly 38 into contact 15 with the face of the drill. The actuating fluid is then admitted to the hammer cylinder 35 to actuate the striker 36.

It will be evident that by the above described arrangement of dolly 38 and forging 20 tools and swages, the drill is operated upon from the end and from all sides without turning the drill over or moving it in any way.

On the bedplate 1 at the front of the frame 25 2 are provided supports 50, 51 for a table, shown consisting of a pair of parallel beams 52 which between them form a guideway for a movable and adjustable stop. The stop which serves to engage and support the 30 shank or rear end of the drill while it is being operated upon by the forging tools, swages, and dolly, is shown consisting of a carriage or cylindrical casting 53 mounted on wheels 54, which are adapted to traverse 35 the upper edges of the parallel beams or girders 52, see Fig. 5. This carriage 53 is cast or otherwise constructed in one piece with a part 55 which traverses longitudinally of and between the beams 52, which form a 40 guide for it. This part 55 is constructed with a horizontal hole 56 and with a vertical recess 57 on the underside. Fitting this vertical recess 57 is a half nut 58 which at its outer end is pivotally connected to a lever 59, 45 which latter is pivotally connected to a lug 60 on the part 55, the lug forming the fulcrum of said lever 59. The lever is turned in an upward direction projecting between the beams 52 to the top of the table, where it is 50 fashioned into a handle 61. 62 is a weight fixed to the lever 59 which serves for keeping the lever depressed and maintaining the half nut 58 in engagement with its actuating screw 63. The screw 63, which is journaled 55 in bearings 64 provided for it between the parallel beams 52, is arranged horizontally and projects through the horizontal hole 56 in the part 55. The half nut 58 engages the thread of the screw 63 so that the latter when 60 rotated serves for advancing or receding the stop 53 according to the length of the drill or bit to be operated upon. 65 is a recess formed in the front of the stop 53 to receive the shank end of the drill and 66 a handle 65 for moving the stop 53 longitudinally of the

table in either direction. For the purpose of rotating the screw 63 to move the stop 53 in either direction to finally adjust the stop 53 I provide a handwheel 67 which is fixed on a spindle 68 supported by one of the beams 52, 70 which spindle 68 on the inside of the beam 52 has fixed to it a bevel wheel 69 which gears with a bevel wheel 70 keyed or otherwise suitably fixed to the screw 63.

In front of and in close proximity to the 75 forging tools and swages 9, 11, I provide a self-centering vise for holding and steady-ing the drill near to the cutting end in order to prevent the bending of the drill or bit and to hold it steady while the dolly 38 is in 80 operation. This vise holds the drill or bit laterally while the adjustable back stop 53 holds it longitudinally, thus the drill is kept in exact position between the tools when being forged. This vise is shown in Figs. 1 85 and 6. It consists of a plate 71 bolted or otherwise suitably fixed to the forward end of the table 52, which plate 71 is constructed to form guides 72 for two nuts 73, the one 90 constructed with a right hand threaded hole and the other with a left hand threaded hole. 74 is a spindle formed with corresponding right and left hand threads engaging said nuts 73. On one end of this spindle 74 is fixed a spur wheel 75 which is engaged by 95 another spur wheel 76 operated by a hand-wheel 77. The spindle 78 to which the hand-wheel 77 and spur wheel 75 are fixed is carried by a lug 79 formed on one of the guides 72. The two nuts 73 are constructed with 100 vertical cylindrical projections 80 on which are mounted the halves 81 of the jaw of the vise, which halves 81 are grooved horizontally to receive the horizontal wings 10 of the drill when in position therein. By rotating 105 the handwheel 77 in one direction the jaws 81 of the vise grip the drill and center it for the forging tools, swages and dolly.

Means are provided for lubricating the 110 forging tools and swages, for removing the scales from between the same, and for keeping the tools cool. These as shown comprise a ring 82, which is fixed to the back of the disk 4 inside the hollow cylindrical projection 5. Between this ring 82 115 and the disk 4 is formed an annular groove 83. 84 is a pipe communicating with a T piece, one branch 85 of which is connected with a source of supply of compressed air, another branch 86 being connected with an 120 oil cup 87. 88 is a cock on the pipe 84 between the cup 87 and T piece for regulating the quantity of lubricant which is permitted to pass from the cup 87 into the T piece. In the disk 4 are formed eight holes 89, one for 125 each tool. These holes 89 communicate with grooves 90 formed in the guideways 8, see Fig. 3, at the back of the tool. These latter grooves 90 communicate with grooves 91 formed in the sides of the guideways 8 and 130

with another groove 92 formed in the front plate 8^a. A small supply of compressed air is preferably kept on when the machine is in operation and this jet of air serves to carry with it the lubricant into the grooves 90, 91, 92, in the disk 4 and plate 8^a surrounding the several tools. The compressed air escapes from between the tools, disk 4 and ring 82 towards the inner ends of the tools and so 10 blows out any scale from the joints between the wearing surfaces, serving at the same time to keep the tools cool and to introduce the lubricant.

The means hereinbefore described and 15 shown in the accompanying drawings for bringing up the corners of the drills or drill bits constitute the subject matter of an application Serial No. 354,629, filed Jan. 29, 1907, as a division of my present case.

20 What I claim as my invention and desire to protect by Letters Patent is:—

1. In apparatus for sharpening rock-drills or bits, in combination, a plate constructed with a central aperture and a plurality of 25 radial guideways, a plurality of forging and swaging tools arranged alternately in said guideways, a frame supporting the plate, yielding and adjustable stops carried by said frame, an oscillatory ring surrounding 30 the plate and carrying means to actuate the tools, and a projection on the oscillating ring which is adapted to engage the adjustable resilient stops to regulate the stroke of the tools, as set forth.

35 2. In apparatus for sharpening rock-drills or bits, in combination, a disk provided with a plurality of radial guideways, a plurality of forging and swaging tools arranged alternately in said guideways, said disk being 40 constructed with a plurality of holes, one for each guideway, grooves formed between the guideways and the tools on all sides and communicating with said holes, a ring fixed to the disk, said ring being constructed with 45 an annular groove communicating with all of the aforesaid holes in the disk, and means for supplying lubricant and fluid under pressure to the annular groove in the ring.

50 3. In apparatus for sharpening rock-drills or bits, in combination, a disk provided with a plurality of radial guideways, a plurality of forging and swaging tools arranged alternately in said guideways, said disk being constructed with a plurality of holes, one for

each guideway, grooves formed between the 55 guideways and the tools on all sides and communicating with said holes, a ring fixed to the disk, said ring being constructed with an annular groove communicating with all of the aforesaid holes in the disk, a pipe 60 communicating with the annular groove in the ring, a compressed fluid supply connected with said pipe, and a lubricant supply also connected with said pipe.

4. In apparatus for sharpening rock-drills 65 or bits, in combination, a disk constructed with a central aperture and with a plurality of radial guideways, a plurality of forging and swaging tools arranged alternately in said guideways, means for actuating said tools, means for holding a drill or bit in said central aperture, a dolly adapted to operate on the end of a drill or bit when held in said central aperture in the disk, means for retracting the dolly to maintain 70 it clear of the face of the drill when the forging and swaging tools are in operation, and means for disengaging said retracting means to maintain the dolly in contact with the end of the drill when the dolly is in operation.

5. In apparatus for sharpening rock-drills 75 or bits, in combination, a disk constructed with a central aperture and with a plurality of radial guideways, a plurality of forging 80 and swaging tools arranged alternately in said guideways, means for actuating said tools, means for holding a drill or bit in said central aperture, a dolly adapted to operate on the end of a drill or bit when held 85 in said central aperture in the disk, a cylinder, a hammer piston therein adapted to strike the dolly, a spring engaging the dolly, means for retracting the dolly and placing 90 said spring in compression, and means for locking the dolly in its retracted position, which locking means when released permit the spring to force the striking face of the 95 dolly into contact with the end of the drill or bit in the aperture in the disk while the 100 dolly is being struck by the hammer piston.

In witness whereof I have hereunto set my hand in the presence of two subscribing witnesses.

WALTER EDWARD KIMBER.
